UNITED STATES PATENT OFFICE.

HENRI PIERRE LAURENT LAUSSUCQ, OF CAMDEN, NEW JERSEY, ASSIGNOR TO HEULINGS LIPPINCOTT AND ALFRED J. MAJOR, AS RECEIVERS OF CAMDEN IRON WORKS, OF CAMDEN, NEW JERSEY, A CORPORATION OF NEW JERSEY.

FILLING SYSTEM FOR PRESSES.

1,357,330.

Specification of Letters Patent.

Patented Nov. 3, 1920.

Application filed January 27, 1919. Serial No. 273,219.

To all whom it may concern:

Be it known that I, HENRI PIERRE LAURENT LAUSSUCQ, a citizen of the United States, residing at 1426 Baird avenue, Camden, in the county of Camden and State of New Jersey, have invented a certain new and useful Filling System for Presses, of which the following is a specification.

My invention relates to hydraulic pressure machines in which two operating systems, including separate pressure cylinders contain or are supplied with equal or proportional quantities of water under pressure which is forced into the cylinders usually by an intensifier, and in which leakage may vary the quantity of water in either or both systems from that intended or in which the proportionate quantities of water in the operating systems may require changing from time to time.

The purpose of my invention is to provide for increase of the total quantity of water in one of two such operating systems, including its cylinder and connections, as compared with the other in order to replace leakage or to vary the proportionate contents and hence vary the relative positions of the pistons in the cylinders.

A further purpose is to maintain a predetermined proportion in the water contents of hydraulic cylinders and their operating connections having common control or to vary the proportions of liquid in the respective cylinders and connections so controlled.

A further purpose is to provide an equalizing valve for selectively varying the total water contents of different cylinders and their operating connections having common control, and to fully protect the valve when not so used from the strain of liquid under pressure.

Further purposes will appear in the specifications and in the claims.

I have preferred to illustrate my invention by but one form, selecting a form which in use has shown excellent results in the control of liquid supply to the cylinders of hydraulic shears; which is simple, highly practicable and very efficient and which at the same time well illustrates the principles of my invention.

Figure 1 is a perspective view showing my invention applied to a hydraulic plate shear.

Fig. 2 is a side elevation, partly sectioned and partly illustrating the same application of my invention.

Fig. 3 is a longitudinal section showing one form of valve by which the filling operation may be performed.

In the drawings similar numerals indicate like parts.

In the hydraulic operation of a die, such as a shear blade having any considerable length and requiring the use of separate cylinders at opposite ends, it is highly desirable that the total liquid contents of each pressure system, *i. e.*, the volumes of water contained in the several cylinders, here uniformly considered as two, and in their respective operating connections) shall be under complete control. This desirability will be seen by consideration of the case of the shear illustrated, in which it is evident that it is necessary to maintain any desired angle of the upper shear blade with respect to the lower blade, for work of a given character even if it be not desired to alter this angle for different characters of work.

The ordinary drain cocks with which the cylinders are equipped provide for letting water out of these systems but do not provide for supplying water to them.

Any leakage, from the cylinders controlling the movement of the upper blade, or from the operating connections therefor, will cause an alteration or change of the rake of the die or shear blade and must be replaced. Again, if it be desired to make any change in the rake of the die or shear blade for the more effective cutting of a different thickness or character of metal sheet, it is necessary to furnish additional motive fluid to one of the pressure systems, either within its cylinder or its connections, as compared with the fluid supply within the cylinder and connections forming the other pressure system.

The construction of the shear and of its intensifier fluid supply are both well known and I have therefore not considered it necessary to give more than a general illustration of their structure. My invention does not reside in the shear or other mechanism operated, whether supplied with operating fluid from an intensifier or not, but in the application of a filling system to the fluid operating systems of any such mechanism.

The frame 5 of the shear is mounted upon

piers 6, and comprises, in so far as description of it is relevant here, a bed 7 carrying a lower cutting die or blade 8, an upper (movable) beam 9, carrying the upper (movable) 5 die or blade 10 and operating mechanism for normally supporting the beam and for moving it downwardly at intervals.

The frame supports a cross head 11, main or pressure cylinders 12, 12' and pull back 10 cylinders 13.

The upper beam 9 is raised resiliently by constant fluid pressure from an accumulator provided for this purpose, conveyed through 15 pipes 14, 15 and 15' to the pull back cylinders and acting through their pistons 16, beam 17 and links 18.

The beam 9 is moved downwardly by pressure cylinder pistons 19, 19' resting in concave seats 20 (Fig. 2) within the upper 20 surfaces of shoes 21. These shoes are movable longitudinally of the beam 9 to accommodate variations in effective length when the rake of the blade 10 is changed.

Where the pull back cylinders are 25 constantly under fluid pressure, as in the illustration and as distinguished from intermittent pull back operation between actuations of the main pistons, the pressure in the main cylinders, or their diameters or, preferably 30 both, must exceed those of the pull back cylinders to an extent determined by the shearing pressure required less the weight of the moving parts. This is usually taken care of by using pistons for the main cylinders 35 which are larger than the pull back pistons, by using a higher accumulator pressure for the performance of the work than for the pull back return and by further increasing the difference between the available pressures 40 through the use of an intensifier of which one form is shown at 22. The accumulator pressure is applied through pipe 23 to the low pressure cylinder 24, and from four high pressure or intensifier cylinders 25 to 45 the operating cylinders of the shear.

The high pressure or intensifier cylinders are connected in pairs to the respective main cylinders 12 and 12' of the shear by pipes 26, 26', the pairs being made up of diagonally opposite cylinders in each case.

This arrangement is well known and results in the supply of equal quantities of liquid to the two cylinders 12 and 12' in the same time where the high pressure cylinders 55 of one intensifier pair are the same size as those of the other pair and could be made to supply any proportionate ratios of liquid to the two cylinders 12 and 12' which the sum of the areas of piston in one pair bore 60 to that of the other pair where a different rate of flow was desired.

Because the general structure for supplying the main intensifier cylinders and the pull-back cylinders in such a construction, 65 is well known, I have not regarded it as

necessary to disclose it, except in the most general way and consider description of the valves and connection for this purpose unnecessary.

With the arrangement shown, with the 70 two diagonally opposite high pressure cylinders of the intensifier feeding one of these main cylinders 12 or 12' and the two intermediate high pressure intensifier cylinders feeding the other thereof, not only are the 75 two pairs of intensifier cylinders intended to deliver motive fluid—water—at the same rate or in a predetermined ratio to the respective pressure cylinders but each of the two fluid pressure operating systems, the 80 shear pressure cylinders and their respective feeding (by which I designate intensifier cylinders and piping) connections must also be full of water to make the pressure effective. Should any of the water leak 85 from either of these fluid pressure operating systems, or should it be desired to advance the one end of the upper, or movable die or blade with respect to the other to change the cutting angle or rake of the movable blade, 90 it will evidently be necessary to introduce additional water within the operating system controlling that end of the blade.

My invention relates to the means and method of maintaining or increasing the 95 fluid contents of pressure systems operating cylinders concurrently, whereby the waste may be replaced or the relative fluid contents may be varied. I accomplish this by tapping the two systems at any convenient 100 points, here within the connecting pipes 26, 26', to feed fluid into one or other of the circuits through filling pipes 27, 27', and a controlling valve 28.

As the "filling" of either pressure system 105 will take place against the pull-back pressure only and the pressure pistons are larger in diameter than the pull-back pistons, the filling fluid can be fed from the accumulator supplying the pull-back cylinders or from 110 that supplying the low pressure intensifier cylinder, or from another source, as preferred. This permits the use of a much lighter valve 28 than would be required if it were necessary to handle the intensified 115 pressure and avoids the necessity of supplying from some other source pressure equal to that supplied by the intensifier.

In order to permit use of the lighter valve, it is necessary to protect the valve from the 120 intensified pressure when the intensifier is being used to operate the shear. The valve is protected from reverse flow of water under intensified pressure by inserting a check valve 29 at a convenient point in each of the 125 feeding pipes 26 or 26' between the controlling valve and the point of connection with the system being filled. These check valves are shown within casings 30 in the illustration.

The body 31 of the controlling valve is provided with an inlet 32, from any suitable fluid pressure source, an exhaust 33 usually to a sewer connection, and two feeding (pressure) outlets, 34, 34' supplying pipes 26, 26'. The piston rod or plunger 35 is moved by a lever 36 pivoted to the piston at 37 and connecting with the body by a link 38.

10 To protect the valve against intensified pressure leaking through the check valves, the valve outlets 34, 34' are normally connected with the exhaust. In the valve shown in Fig. 3 this takes place in the neutral position of the valve shown in Figs. 2 and 3.

The inlet 32 opens into an annular recess 39 about a bushing 40 apertured at the center at a number of points, as at 41. The bushing is retained, longitudinally by a cabled 20 flange 42 at one end and a fixed flange 42' at the other entering corresponding enlargements of the valve bore. At each end of the bushing annular recesses 43, 43' connect at all times with outlets 34, 34'.

25 At their outer ends recesses 43, 43' are closed by packing 44, 44' which is held in place on one side of each by flanged rings 45. On the other side, at one end it is held by inner (here interiorly flanged) ends 46 of 30 a tubular (glanded) closure 47 and at the other end by a cap 48. The rings 45 seat against body flanges 49 on the inner sides and on the outer sides their flanges 50 chainel the facing sides of the ring packing, both 35 retaining and spreading it.

Except for the gland and packing at 51 for the piston rod, the glanded closure 47 and cap 48 are duplicates, being threaded into the body at 52, 52', packed at 53, 53' and 40 provided with tubular extensions 54, 54' whose interiors 55, 55' are constantly in communication with the exhaust 33 through apertures 56, 56', annular spaces 57, 57' and exhaust channels 58, 58'.

45 The valve spindle or plunger 35 carries its operating parts between a flange 59 near one end and a suitable locked nut 60 at the other. These parts comprise oppositely facing counterpart members.

50 At the center, by means of two facing cupped packing rings 61, 61' spaced by collar 62, I provide an extended sealing surface, sealing the inlet from the rest of the valve at the middle plunger position.

55 The rings are held in place at their outer sides by facing annular flanges 63, 63' upon tubes 64, 64'. Upon these tubes are mounted sleeves 65, 65' of larger internal diameters than the external diameters of the tubes, 60 providing annular spaces 66, 66' between, which are open at their inner ends at 67, 67'.

The sleeves are each apertured at two axially separated points 68, 69 and 68', 69' so chosen that for each sleeve they lie on opposite sides of the packing 44, 44' in the

middle position of the plunger, but on the same side of this packing in the extreme plunger positions; being then, both between the packing and the inlet 32 at one end, and both beyond the packing from the inlet 32 70 at the other end of the valve.

In operation:—In the neutral (middle) position of the valve plunger shown in Fig. 3, and to which the position of the parts in the other figures corresponds, the accumulator pressure through valve inlet 32 is held by packings 61, 61' from communication with the rest of the valve. Even if they leak, no harm will be done as the leakage flow would enter the open ends 67, 67' of 80 spaces 66, 66' and pass to the exhaust through apertures 68, 68', spaces 55, 55', and apertures 56, 56'.

Since both of the outlet connections 34, 34' are in communication with the exhaust 85 through apertures 69, 69', spaces 66, 66' and the path above described, leakage of intensifier pressure past the check valves will pass to the exhaust, relieving the valve wholly from intensifier pressure. 90

When the plunger is moved to either extremity of its stroke the action is the same, the only difference being as to which of the outlets 34 or 34' is connected with the inlet 32 to fill, the other remaining in communication with the exhaust. I will therefore describe but one of them.

If the plunger be moved to the right (in Fig. 3) the packing 61 passes the apertures 41 and the inlet communicates freely with outlet 34 apertures 41, space 66 and apertures 68 or 69. Since the apertures 68 pass the packing 44, this packing shuts off the path to the exhaust.

Though movement of the plunger to the 105 right cuts off the connection of outlet 34' with space 66' through apertures 69' it does not cut off communication through this space to the exhaust, as the water from outlet 34' is free to enter the open end 67' of 110 this space.

In either event the valve piston is moved so as to admit accumulator pressure through the appropriate end of the valve and the corresponding check valve to that pressure 115 system from which the leakage has taken place, or within which the motive fluid is otherwise additionally required.

It will thus be seen that between the drainage taps and the filling system herein 120 provided, the total quantity of motive fluid in each of the pressure systems may be adjusted, as well as the proportion which these bear to each other, providing a flexibility and control not otherwise attainable. 125

When filling is not needed, the shear or other device may be operated as usual without in any way affecting the filling connection. When it is desired to fill either pressure system the controlling valve plunger 35 130

is moved in the appropriate direction and is retained there until the filling operation is completed.

Having thus described my invention, what I claim as new and desire to secure by Letters Patent is:

1. In a device of the character stated, an intensifier, having two separate outlets therefrom, proportionately supplied from 10 said intensifier, a pair of cylinders fed from said outlets, mechanism operated by the pistons of the cylinders, pistons therein, connections between the intensifier and the two cylinders forming two pressure systems one 15 for each cylinder and selective means for supplying fluid to either system.
2. In a device of the character stated, a pair of hydraulic cylinders, pistons therein, mechanism operated by the pistons, separate 20 pressure connections for said cylinders at a constant proportion one to the other, a source of pressure supply and connections for selectively applying said source of supply to either of said cylinders and connections to fill the one without filling the other.
3. In a device of the character stated, an intensifier having separate fluid paths and outlets, two pressure cylinders and connections from one to each of said outlets forming 30 with the intensifier separate pressure systems fed proportionately from said accumulator, in combination with a source of pressure supply, connections therefrom to the two pressure systems, and a check valve 35 in each connection.
4. In a device of the character stated, an intensifier having separate fluid paths and outlets, two pressure cylinders and connections from one to each of said outlets forming 40 with the intensifier separate pressure systems fed proportionately from said intensifier, in combination with a source of pressure supply, connections therefrom to the two pressure systems and a check valve 45 in each connection said connections being normally at exhaust between the check valve and the pressure supply.
5. In a device of the character stated, a pair of pressure systems including cylinders 50 and pistons therein, and a filling system for said pressure systems, comprising a valve having inlet, exhaust and two outlets normally connected with the exhaust, but selectively connected with the inlet in other positions of the valve, connections from the two outlets to the two pressure systems and a check valve in each connection preventing the fluid from the pressure systems from returning to the valve.
6. In a device of the character stated, a pair of cylinders, pistons therein and mechanism operated by the pistons, a constantly operating return for the mechanism and pistons, distinct fluid pressure supplies for said 65 cylinders normally unchanged in fluid con-
- tent, comprising with the cylinder contents pressure systems, a connection with each system, a check valve in each connection and fluid pressure filling means normally at exhaust for selectively filling either system 70 through its check valve.
7. In a device of the character stated, an intensifier having separate high pressure cylinders, a pair of operating cylinders, each connected with different intensifier cylinders, forming separate pressure systems, a piston in each operating cylinder, mechanism operated by the pistons, pull-back connections for the mechanism and means for varying the fluid content of the two pressure systems comprising connections with the two systems, a check valve in each connection, a fluid pressure supply and means for directing the fluid pressure supply selectively through either check valve at will, 80 the supply being normally cut off from the said means and said means being at exhaust.
8. A filling system for presses comprising a valve having an inlet, an exhaust and two outlets, the latter spaced on opposite sides 90 axially of the inlet and normally connected with the exhaust, a valve piston movable in opposite directions to connect the inlet and either outlet at will, connections from the outlets of the valve and a check valve in 95 each of said connections preventing fluid movement toward the valve.
9. A filling system for presses, comprising a valve having an inlet, an exhaust and two outlets, the latter spaced on opposite sides 100 axially of the inlet and normally connected with the exhaust, a valve piston movable in opposite directions to connect the inlet and either outlet at will while maintaining the other outlet at exhaust, connections from the 105 outlets of the valve and a check valve in each of said connections preventing fluid movement toward the valve.
10. A filling system for selectively filling either of two hydraulic pressure systems, 110 which consists in a valve having a central inlet, end exhausts and intermediate outlet connections, a valve piston normally cutting off the inlet from both outlets and connecting the outlets with the exhaust and, in 115 positions on opposite sides of its normal position, connecting one or other of the outlets with the inlet, means for operating said piston, and connections from said outlets, there being a check valve in each outlet connection.
11. A filling system for selectively filling either of two hydraulic pressure systems which consists in a valve having a central inlet, end exhausts, and intermediate outlet 125 connections, a valve piston normally cutting off the inlet from both outlets and connecting the outlets with the exhaust and in positions on opposite sides of its normal position connecting one or other of the outlets with 130

the inlet, the other outlet being maintained in connection with the exhaust, means for operating said piston, and connections from said outlets, there being a check valve in 5 each outlet connection.

12. In a filling system for hydraulic machinery, a closed hydraulic pressure system to be filled, a connection therewith, a check valve in the connection preventing fluid 10 movement away from the system, a filling pressure supply and a valve between the filling pressure supply and the check valve normally maintaining the main interior part of the valve at exhaust.

15 13. A filling system for hydraulic machinery having filling pressure supply, valve

distribution therefor and check valve protection for the connections between the distributing valve and the systems to be filled and having these connections normally connected to the valve exhaust. 20

14. A filling system for hydraulic machinery comprising a pair of closed fluid pressure systems to be filled, a filling pressure supply, a distributing valve for said 25 supply, check valves between the distributing valve and the systems to be filled and means within the distributing valve for protecting it against pressure from the systems being filled in case of leakage of the check 30 valve.

HENRI PIERRE LAURENT LAUSSUCQ.
